his Attorneys.

UNITED STATES PATENT OFFICE.

SAMUEL E. DIESCHER, OF PITTSBURGH, PENNSYLVANIA, ASSIGNOR TO S. DIESCHER & SONS, A PARTNERSHIP CONSISTING OF SAMUEL E. DIESCHER AND AUGUST P. DIESCHER, OF PITTSBURGH, PENNSYLVANIA.

TIN-PLATE-CLEANING MACHINE.

Application filed January 28, 1927. Serial No. 164,221.

This invention relates to apparatus for cleaning tin plate.

In the manufacture of tin plate it is well known that plate is passed through a body of molten tin and then through a body of grease, usually palm oil, which rests upon the molten tin at the discharge side of the pot. While the plate is passing through the upper portion of the grease its coating of tin becomes set, and after it passes out of the pot the layer of grease adhering to it prevents oxidation of the tin while the plate is still hot. After the plate is cooled to a temperature below that at which the tin oxidizes in the atmosphere, the layer of grease not only serves no useful purpose, but must be removed to render the plate commercially useful. The usual practice in removing grease from tin plate is to pass the plate through what is known as a branning machine in which bran is variously rubbed upon the surfaces of the plate. However, in the present forms of plate-cleaning apparatus, considerable difficulty has arisen by reason of inability to entirely remove the grease, and unless it is entirely removed the plate has a blue cast which is prejudicial to the effective use of the plate for lithographic purposes.

The present invention is predicated upon my discovery that an important factor in the thorough cleaning of tin plate to render it free from blue cast is the temperature of the bran used in the cleaning apparatus. I have found that unless the bran is maintained at a temperature not higher than about 140 degrees F. it is impossible to remove the blue cast from tin plate. Accordingly, it is the object of this invention to provide tin plate cleaning apparatus with means for maintaining the bran or equivalent cleaning material at a temperature of below that stated.

The invention is illustrated in the accompanying drawings, of which Fig. 1 is a combined side elevation and longitudinal sectional view of a plate cleaning apparatus; Fig. 2 a longitudinal central sectional view of a roll used in the apparatus, the plane of view being indicated by the line II--II, Fig. 1; and Fig. 3 a sectional view of a portion of the bottom of the cleaning apparatus, the plane of view being indicated by the line III--III, Fig. 1.

In the practice of this invention a box,

provided with bran or equivalent cleaning material and having means for applying the bran to tin plate passed through it, is provided with means for cooling the bran in the box. While various means may be provided for so cooling the bran, this is preferably done by cooling the means, or a portion of them, used for applying the bran to plate, and by cooling the means for circulating the bran in the box.

The tin plate cleaning apparatus shown in the drawings is similar in its general features of construction to that shown in my Patent No. 1,279,672. The machine comprises a box 1 provided with a series of pairs of rotatable cleaning rolls, between which plate is passed, and by which bran is applied to its surfaces. To gain the advantages explained in my Patent No. 1,155,711, one of each of these pairs of rolls is preferably formed of metal and the other of felt, the metal and felt rolls being arranged alternately in successive pairs, the metal roll being the lowermost in one and the uppermost in the adjacent pairs of rolls. At the entering end of the box there is preferably arranged a pair of combined feed and plate-cleaning metal rolls 4, to the surfaces of which some of the grease from the plates adheres, and from the surfaces of which this adhering grease is continuously removed by suitable cleaners or scrapers 5.

In the bottom of box 1 there are a plurality of screw conveyors 6 or equivalent means for causing bran carried forwardly by the plate to be moved towards the entering end of the box in a direction opposite to that of the movement of the plate through the box.

It has previously been explained that according to this invention some of the bran-applying mechanism is cooled to maintain the bran at a low temperature. In the illustrative embodiment of the invention provision is made for cooling some or all of the lowermost metal rolls 3. As shown particularly in Fig. 2, such rolls may be formed of a metal cylinder 10 provided with heads 11 and 12. Through the head 11 there extends a pipe 13 to which water or other cooling medium is supplied through a pipe 14 suitably connected to it. Within cylinder 10 pipe 13 is provided with perforations for the discharge of water, which then flows from the cylinder through passages 15 and 16 formed

in head 12, the passage 16 being suitably connected to a discharge pipe 17. By thus cooling the lowermost metal rolls 3, it has been found that the temperature of the bran 5 may be maintained materially below 140 degrees F.

As an alternative construction, or for use in conjunction with cleaning apparatus including water cooled metal rolls, provision is 10 made for cooling the bottom of box 1 on which bran is supported as it is moved towards the entering end of the cleaning mechanism. As shown particularly in Fig. 3, the bottom of the box is shaped to form a plurality of 15 troughs 20, in each of which there is arranged the screw conveyor 6. For cooling the bottom of the box it is preferably made of double wall construction affording a passage 21 for the flow of water which may enter the passage 20 through a supply inlet 22 and be discharged from it through an outlet 23. To 20 avoid the formation of air pockets in passage 21 between troughs 20, outlet pipes 26 extend upwardly from outlet 23 between the troughs. 25 In the operation of the cleaning mechanism, the plate is fed to it from a suitable conveyor 25, and is passed into the box 1 by the metal feed rolls 4, to the surfaces of which some grease adheres. This grease is removed 30 from the rolls by the scrapers 5. The plate then passes between successive pairs of rolls 2-3, the members of which are so driven at different relative speeds that, in addition to 35 conveying the plate through the bran, they rub the bran upon the faces of the plate and carry the bran from the entering towards the exit end of the box. As the plate moves through the box the bran falls from it and is moved forwardly by conveyors 6. By its contact with the lowermost water cooled metal 40 rolls 3, and with the bottom 20 of the box, the bran is cooled so that it is rendered effective for so removing the grease from tin plate that plate does not have a blue cast or any harmful greasy character of surface.

According to the provisions of the patent statutes, I have explained the principle and operation of my invention and have illustrated and described what I now consider to 50 represent its best embodiment. However, I

desire to have it understood that, within the scope of the appended claims, the invention may be practiced by other forms of construction than those particularly shown and described.

55

I claim as my invention:

1. In a machine for cleaning tin plate, the combination of a box provided with a cleaning material, a series of pairs of rotatable rolls in the box by which such material is applied to the surfaces of tin plate as it is passed between the rolls, means including troughs for moving the cleaning material in a direction opposite to that of the passage of plate through the machine, and means for cooling 60 said troughs to in turn cool the cleaning material in said box.

2. In a branning machine for cleaning tin plate, the combination of a box adapted to be provided with bran, means in said box for 70 applying the bran to tin plate for cleaning it, and means for cooling the bran within the box.

3. In a branning machine for cleaning tin plate, the combination of a box adapted to be 75 provided with bran, a series of pairs of rotatable rolls in the box by which the bran is applied to the surfaces of tin plate as it is passed between the rolls, and means for cooling the bran within the box.

4. In a machine for cleaning tin plate, the combination of a box adapted to be provided with bran, a series of pairs of rotatable rolls in the box by which the bran is applied to the surfaces of tin plate as it is passed between the rolls, some of said rolls being metal cylinders, and means for cooling the metal cylinder rolls to in turn cool the bran in said box.

5. In a machine for cleaning tin plate, the 90 combination of a box adapted to be provided with bran, a series of pairs of rotatable rolls in the box by which the bran is applied to the surfaces of tin plate as it is passed between the rolls, the lowermost roll of alternate pairs 95 of said rolls being a metal cylinder, and means for cooling said lowermost metal cylinder rolls to in turn cool the bran in said box.

In testimony whereof, I sign my name.

SAMUEL E. DIESCHER.
